UNITED STATES PATENT OFFICE.

FRANK SCHREIDT, OF MANSFIELD, OHIO.

FOUNTAIN-BRUSH.

1,082,288.

Specification of Letters Patent. Patented Dec. 23, 1913.

Application filed May 29, 1913. Serial No. 770,625.

To all whom it may concern:

Be it known that I, FRANK SCHREIDT, a citizen of the United States of America, residing at Mansfield, in the county of Richland and State of Ohio, have invented certain new and useful Improvements in Fountain-Brushes, of which the following is a specification.

This invention relates to certain new and useful improvements in fountain brushes, and pertains more particularly to shaving brushes.

The primary object of the invention is to provide improved means, of simple, efficient and economical structure, for positively feeding paste, powder, cream, soap, or any desired fluid to the brush bristles.

Further the invention aims to provide means which can be easily and quickly operated to regulate the amount of discharge of paste into the brush bristles, and to also provide a structure in which danger of leakage is reduced to a minimum.

Still further the invention aims to provide means for enabling the plunger and associated parts to be easily and quickly removed from the magazine.

In the drawings: Figure 1 is a side elevation, partly broken away, and in section, of the invention; Fig. 2 is a section on the line 2—2 of Fig. 3; Fig. 3 is a detail view, showing a part of the apparatus in side elevation; Fig. 4 is a view similar to Fig. 1, of a modified form of the invention; and Fig. 5 is a section on the line 5—5 of Fig. 4.

A magazine 1, is closed at one end by a closure 2, which is threaded into engagement therewith, and which has its inner surface forming a continuation of the bore of the magazine. Centrally of the length of the magazine same is provided with a tapered part 3 which communicates with a contracted end part 4 that is formed with a passage 4' the free outer extremity of the end part 4 of the magazine is formed with a valve seat 5, which latter co-operates with a valve 6 that is for engagement with the valve seat 5. The valve 6 is formed on an end 7 of a cap 8 that is slidably and rotatably mounted over the end part 4 of the magazine. A series of apertures 9 extend through the end 7 of cap 8 to convey the paste from the magazine to the brush bristles. The apertures 9 align with the extremity of the end part 4, so that when the valve 6 is closed, the apertures will also be

closed by seating on the said extremity of part 4.

The periphery of the end part 4 is formed with an inclined or cam groove 10 into which the inner end of a set screw 11 projects, the set screw being carried by a sleeve 12. The sleeve 12 slides over the part 13 that is located on the magazine and is formed with a flange 14 that extends inwardly of the sleeve and supports packing 17, which packing is engaged by the lower end of the cap 8. The lower end of the cap 8 is threaded into engagement with the sleeve 12 and has a peripheral flange 18 on which the brush bristles 19 may seat, the bristles being secured in any suitable manner between the cap 8 and the upper free end portion of the sleeve 12.

The sleeve 12 has a knurled portion 20 to facilitate easy operation thereof and since the cap is rigidly connected to the sleeve and moves therewith, it will be seen that the valve 6 may be regulated to permit the desired feed of paste through the passage 4' by operation of the sleeve. A plunger 21 is connected to a stem 22 and operates within the magazine 1, the stem passing through a stuffing box 23 that is attached to the closure 2 and having an operating head 24 on its outer end.

In the modified form shown in Figs. 4 and 5 of the drawings, the construction is the same as that above described, with the following exceptions: The part 4 has a transverse bridge member 25 that has a central aperture 26 which rigidly receives and holds therein a threaded stem 27. A sleeve 28 receives the stem 27 and has a part 29 which is provided with a threaded aperture that receives the stem 27, the sleeve passing through the stuffing box 23 attached to the closure 2 and having an operating head 30 attached rigidly to its outer end. A plunger 31 is rigidly attached to the part 29 of the sleeve and moves with the latter. Movement imparted to the sleeve through the medium of the head 30, will cause the part 29 of the sleeve to ride the threads of the immovably held stem 27 with the result that the plunger will be correspondingly moved. In this form of the invention, a threaded connection 31' is formed between the sleeve 32 and the magazine 1, a stop flange 33 limiting the opening movement of the valve 6 borne by the cap 8 which latter is connected to the sleeve 32. The sleeve 32 is formed of

two parts threadedly connected at 34. Since the bore of the closure 2 and that of the magazine 1 register, it will be seen that the plunger 21, can be drawn into the closure 2 and easily removed. Likewise in replacing the parts, the plunger centers the closure so that the latter can be easily replaced, without mutilation of the washers. It will also be noted that the threaded interior of the closure 2 will readily engage the threaded exterior of the magazine without interference from the washers.

What is claimed is:

1. In a brush of the type set forth, a magazine having a tapered part terminating in a contracted end part having a passage, a valve seat formed on the free extremity of said end part, a cap movably mounted over the magazine and having a closed end formed with apertures which apertures align with the extremity of said end part, a valve carried by the cap for engagement on said valve seat, means to adjust the cap to regulate the extent of movement of the valve to and from its seat, and means in the magazine to force paste or the like through the magazine and through said apertures of the cap.
2. In a brush of the type set forth, a magazine having a valve seat on its discharge end, a cap slidable on the magazine and having a valve on one end for engagement on said valve seat, said end of the cap having apertures which surround the valve and which align with said end of the magazine to be closed thereby when the valve is in closed position, and means to enable adjustment of the cap.
3. In a brush of the type set forth, a magazine having a valve seat on its discharge end, a cap slidable on the magazine and having a valve on one end for engagement on said valve seat, said end of the cap

having apertures which surround the valve and which align with said end of the magazine to be closed thereby when the valve is in closed position, bristles surrounding the cap, a sleeve borne by the cap, said magazine having a diagonal peripheral groove, and a projection carried by the sleeve and 50 extending into the groove.

4. In a brush of the type described, a magazine having a discharge end formed with a valve seat, a cap having a valve at one end to engage said seat, a sleeve threaded on the cap, said sleeve having an interior flange, packing between the flange and the lower end of the cap, means to adjust the cap, and means to force paste through the discharge end of the magazine.

5. In a brush of the type described, a magazine having a discharge end formed with a valve seat, a cap having a valve at one end to engage said seat, a sleeve threaded on the cap, said sleeve having an interior flange, packing between the flange and the lower end of the cap, said magazine having a peripheral cam slot, a pin carried by the sleeve and extending in said slot, and means in the magazine to force paste through the 70 discharge end of the magazine.

6. In a brush of the type set forth, a magazine having a valve seat at its discharge end, a cap having a valve for engagement with the seat, bristles surrounding the 75 cap and valve, a sleeve surrounding the bristles, means to adjust the sleeve and thereby the valve, and means to force paste or the like through the magazine.

In testimony whereof I affix my signature 80 in the presence of two witnesses.

FRANK SCHREIDT.
